(57) **CLAIM**

The ornamental design for a clip-on child handle, as shown and described.

DESCRIPTION

FIG. 1 is a front perspective view of a first embodiment of a clip-on child handle showing my new design;

FIG. 2 is a rear elevational view thereof;

FIG. 3 is a side elevational view, the opposite side being a mirror image thereof;

FIG. 4 is a front elevational view thereof;

FIG. 5 is a top plan view thereof;

FIG. 6 is a bottom plan view thereof;

FIG. 7 is a front perspective view of a second embodiment of my design of FIG. 1;

FIG. 8 is a rear elevational view of FIG. 7;

FIG. 9 is a side elevational view of FIG. 7, the opposite side being a mirror image thereof;

FIG. 10 is a front elevational view of FIG. 7;

FIG. 11 is a top plan view of FIG. 7; and,

FIG. 12 is a bottom plan view of FIG. 7.
